UNITED STATES PATENT OFFICE.

NELSON HORNADAY, OF WEST ELKTON, OHIO, ASSIGNOR TO HIMSELF AND
Z. STUBBS.

IMPROVEMENT IN PORTABLE FENCES.

Specification forming part of Letters Patent No. 36,215, dated August 19, 1862.

To all whom it may concern:

Be it known that I, NELSON HORNADAY, of West Elkton, Preble county, Ohio, have invented a new and useful Improvement in Portable Fences; and I do hereby declare the following to be a full, clear, and exact description thereof, reference being had to the annexed drawings, making part of this specification.

This improvement relates to a form of fence for combining with the advantages of durability those of great facility of construction, erection, and removal, the invention consisting, chiefly, in a peculiar construction of chair or upright having a pair of oblique braces hinged at their lower extremities to a horizontal sill-piece and notched at their upper extremities, which act to grasp the panels by the weight of the fence alone.

Figure 1 is a perspective view of my improvement. Fig. 2 is a transverse section thereof.

My chair or upright consists of a triangular frame of boards—namely, a horizontal sill, A, and two oblique braces, B B', of which one is hinged to each end of the sill by means of a stout nail, C. The top of each brace has a rectangular notch, D, longitudinal of the fence. The tops of the braces being overlapped, as represented, the two notches unite to form a seat, D D, longitudinal with respect to the fence for the contiguous ends of two upper rails, E E', of a pair of consecutive panels.

It is apparent that the weight of the panel, acting to depress the braces, causes the vertical sides d d of the seat to compress tightly the sides of the panel-rails, so to firmly hold the upper portion of the panels by the mere weight

thereof without the use of pins, which, besides their cost, introduce moisture and decay and cause the fence speedily to give down.

A notch, F, in the sill holds the lower portion of the panels against lateral displacement, but is of such depth as not to interfere with the downward stress of the panels in the seat D D.

A single panel may be removed from a line of fencing by shifting two adjacent chairs laterally and obliquely of the fence and then lifting out the panel. This operation, although brief and simple, demands intelligence and consecutive performances beyond the comprehension of animals.

It will be seen that the entire fence may be constructed of boards and a few nails, the braces being got out without waste, because the same cut which forms the notched top of one brace completes the bottom of another.

I claim herein as new and of my invention—

The arrangement of oblique braces B B', secured at their lower ends by pivots C C to a sill, A, and provided at their upper ends with notches D D, running longitudinally of the fence and forming a seat for the contiguous ends of the rails of two adjacent panels to rest in, the whole being combined in such a manner that the downward stress of the panels continually acts to firmly support and clamp the parts together, substantially as described.

In testimony of which invention I hereunto set my hand.

NELSON HORNADAY.
